DRILL HOLE CLEANING DEVICE

Raymond L. Crow, Lawrence, Kans.

Application October 20, 1936, Serial No. 106,667

5 Claims. (Cl. 255—60)

This invention relates to new and useful improvements in devices for removing drillings, such as rock dust, from the bottom of drill holes of any depth.

5 Considerable difficulty has always been experienced in the removal of dust or drillings from holes formed in rock and other sub-soil strata. The usual methods used to accomplish the removal of the rock dust or drillings have been to 10 blow the dust out of the hole, draw it out by suction, or float it out with water, or the like. All of these methods tend toward a considerable waste of very valuable time.

It is the primary object of this invention to 15 provide a device which will quickly and easily accomplish the removal of rock dust, or other drillings, from drilled holes resulting in the saving of considerable time which has been wasted in the removal of rock dust by old methods.

20 Other objects and advantages of the invention will be apparent during the course of the following description.

In the accompanying drawing forming a part 25 of this specification and in which like numerals are employed to designate like parts throughout the same,

Figure 1 is a side elevational view of one form of drill hole cleaning device embodying this invention,

30 Figure 2 is a side elevational view, partly broken away, of a modified form of drill hole cleaning device, and

Figure 3 is a side elevational view of a still further modified form of drill hole cleaning device with a sharpened ferrule shown separated 35 from the inner end of the main body of the device and with the upper portion of the handle broken away.

In the drawing, wherein for the purpose of 40 illustration are shown the preferred embodiments of this invention, and particularly referring to Fig. 1, the reference character 5 designates the body portion of a section of flexible tubing which may be of any desired length. The opposite ends of this section of tubing are provided with ferrules 45 6. These ferrules may be formed as an integral part of the ends of the tubing or they may be formed as separate rings and suitably secured to the ends of the tubing.

50 A modified form of drill hole cleaning device is illustrated in Fig. 2. This form consists of a section of flexible tubing 7 which also has a ferrule 8 either formed integrally with one end thereof or constructed as a separate ring to be welded, or the like, to the end of the tubing 7.

The remaining end of the tubing 7 has suitably secured thereto, as by welding or the like, a coupling member 9 to the bore of which is threadedly connected a tubular handle 10. The upper end of this handle is enlarged at 11 to provide a smooth bearing surface to be engaged by the hand of the operator of the device. The bore of the tubular handle 10 is in open communication at its inner end 12 with the bore of the flexible tubing 7. This handle bore also extends through 10 the center of the enlarged head 11, as at 13. This provision of a handle 10 with its bore opening through opposite ends of the same permits air to enter the upper end of the flexible tubing 7.

A still further form of drill hole cleaning device is illustrated in Fig. 3. In this form of the invention, the body portion consists of a section of flexible tubing 14. A ferrule 15 is adapted to be detachably, threadedly connected to the inner end 16 of the body portion of the tube 14. This threaded connection is accomplished by forming a spirally extending rib 17 on the ferrule 15 which cooperates with the spiral groove 18 of the tubing 14. A coupling member 19 is suitably secured to the remaining end of the tubing 14 20 and is formed with an externally threaded, reduced portion 20 to which is threadedly connected the inner end portion of a tubular handle 21.

It is to be understood that each one of the 25 sections of flexible tubing 5, 7 and 14 is of the same construction. This construction is illustrated in the sectional portions of Fig. 2. Each one of these tubing sections is formed from a ribbon of suitable material, such as metal, with the ribbon being of shallow channel formation, as 30 designated by the reference character 22. One longitudinal edge of this ribbon is formed with a relatively narrow reversely curved flange 23 which, due to its curvature, provides an external 35 groove 24. The remaining longitudinal edge of the channel shaped ribbon, in the spiral winding of the ribbon to form the tube, is seated in this external groove 24.

Fig. 2 also discloses the outer edge of the ferrule 8 as being sharpened, as at 25. It is to be 40 understood that each one of the ferrules 6 is provided with a sharpened edge 25 of the form shown in section in Fig. 2. The ferrule 15, disclosed in Fig. 3, also is provided with a sharpened edge 25.

In the use of these tools for removing rock 45 dust, or other drillings, from the bottom of a drill hole, the tool is jammed or forced into the drill hole. This inward forcing or jamming of the devices into drill holes causes the rock dust, or 50

55

the like, to be forced up into the bores of the tubings. The flanged edges 23 and the channel portions 22, extending spirally throughout the length of each of the tubings 5, 7, and 14 function to pack and hold the rock dust in the tubings. After the devices have been jammed into the drill holes, rotation of the devices will cause the rock dust, or the like, received within the bores or the tubing to be separated or severed from the dust remaining in the bottom of the drill holes. The tools then may be removed from the drill holes and the rock dust held within the bores of the tubings may be quickly and easily removed therefrom by merely striking the tubings against the ground, or other solid object.

It is to be understood that I do not desire to limit myself to the use of a flexible tubing for any form of tubing which is formed with a bore having a channel, ledge or shelf formed spirally throughout the bore thereof will accomplish the desired results to a practical extent. The flexible tubing illustrated in the several figures, however, operates most successfully and permits much more ready removal of the drillings from the bores of the tubes.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:

1. A drill hole cleaning device comprising a section of flexible tubing having a sharpened edge at one end thereof, a tubular handle open at both ends, means for connecting said tubular handle

to one end of the tubing with the bores of the handle and tubing in open communication, and spirally extending means formed in the bore of said section of tubing for packing and holding drillings received therein when the device is forced into a drill hole.

2. A drill hole cleaning device comprising a section of flexible tubing, and spirally extending means formed in the bore of the tubing for packing and holding drillings received therein when the device is forced into a drill hole.

3. A drill hole cleaning device comprising a section of flexible tubing having a sharpened edge at one end thereof, and spirally extending means formed in the bore of the tubing for packing and holding drillings received therein when the device is forced into a drill hole.

4. A drill hole cleaning device comprising a section of flexible tubing, a tubular handle open at both ends, means for connecting said handle to one end of the tubing with the bores of the tubing and handle in open communication, and spirally extending means formed in the bore of the tubing for packing and holding drillings received therein when the device is forced into a drill hole.

5. A drill hole cleaning device comprising a section of tubing, and a handle member for manipulating the tubing, said tubing consisting of a spirally wound ribbon having a channel cross-sectional formation, and means for connecting the edge portions of adjacent convolutions of the ribbon to permit limited relative movement between said edge portions to provide for flexing of the tubing.
